United States Patent

Des. 240,715
Patented July 27, 1976

240,715

TISSUE BOX COVER OR SIMILAR ARTICLE

Ralph R. Schwartz, 11 Cypress Road,
East Chester, N.Y. 10709

Filed June 7, 1973, Ser. No. 367,718

Term of patent 14 years

Int. Cl. D9—99

U.S. Cl. D9—259

Fig. 2

FIG. 1 is a perspective view of a tissue box cover showing my new design; and

FIG. 2 is a front elevational view thereof. The surfaces not shown are plain and unornamented.

I claim:

The ornamental design for a tissue box cover or similar article, substantially as shown and described.
